Thomas A. Keen, San Mateo, Calif., assignor to Hannah M. Smith, River Forest, Ill.

Application November 28, 1938, Serial No. 81,436

Term of patent 14 years

To all whom it may concern:

Be it known that I, Thomas A. Keen, a citizen of the United States, residing at San Mateo, in the county of San Mateo and State of California, have invented a new, original, and ornamental Design for a Starting Box, of which the following is a specification, reference being had to the accompanying drawing, forming part thereof.

Fig. 1 is a front view, and

Fig. 2 is a perspective view of a starting box embodying my new design.

I claim:

The ornamental design for a starting box, substantially as shown.

THOMAS A. KEEN.
